UNITED STATES PATENT OFFICE.

SAMUEL B. FINEGAN, OF EUGENE, OREGON.

SPRING-FORMING MACHINE.

1,276,639.

Specification of Letters Patent. Patented Aug. 20, 1918.

Application filed February 13, 1917. Serial No. 148,358.

To all whom it may concern:

Be it known that I, SAMUEL B. FINEGAN, a citizen of the United States, residing at Eugene, in the county of Lane and State of Oregon, have invented new and useful Improvements in Spring-Forming Machines, of which the following is a specification.

It is the primary object of this invention to provide a machine for forming vehicle 10 springs to a regular or irregular pattern in a quick and convenient manner.

The following description is addressed to the use of the machine in the formation of vehicle springs, which is believed to be sufficiently characteristic of its utility and admirably illustrates the invention, but it is desired to have it understood that the machine is susceptible for use in other metal forming capacities, and its general application 20 is contemplated by the claims.

In carrying out the invention I provide the table or support for the work with an adjustment to accommodate itself to materials of different dimensions.

25 In the drawings forming part of this specification like numerals of reference indicate similar parts in the several views and wherein:—

Figure 1 is a top plan view.

30 Fig. 2 is a vertical transverse sectional view.

Fig. 3 is a longitudinal sectional view.

Fig. 4 is a detail view of one of the brackets and cam lever.

35 Fig. 5 is a detail view of one of the spring engaging clips.

Fig. 6 is a fragmentary view of the angle bar.

Fig. 7 is a fragmentary detail view of one 40 of the plungers.

The remaining figures are detail views of several of the parts.

The preferred embodiment of the invention herein illustrated consists of a table 45 constituting the work support, and including the legs 10 which are connected by the transversely and longitudinally disposed brace bars 11 and 12 respectively, and a top 13 whose width is such as to terminate 50 short of one side of the structure as a unit. Mounted upon the top 13 adjacent one edge is a plurality of U-shaped clips 14 disposed in spaced relation and each having slidably fitted therebetween and the top 13 a sub- 55 stantially L-shaped arm 15, the arms col-

lectively constituting a support for the pattern 16 which in this particular instance consists of a substantially semi-elliptical metallic band. The arms 15 are independently movable to assume different positions 60 relatively depending upon the particular design of pattern which they are to support. A heated spring leaf or other piece of material 17 is placed upon the table top to bear against the intermediate portion of the pattern 16 to be formed to fit the pattern 65 through the instrumentality of a plurality of plunger rods 18 which are mounted to slide transversely across the table top 13 and brought into engagement with the spring leaf 17, thereby forcing the latter into engagement with the pattern to be shaped in a like manner. Spaced angle bars 19 extend longitudinally of the table in parallelism, and constitute supports for the 70 plunger rods, which latter slide through suitable openings in the vertical flanges of the angle bars. A flat equalizing spring is indicated at 20 and normally disposed adjacent the outermost angle bar 19 in parallelism therewith. Mounted upon the equalizing spring is a plurality of brackets 21, there being one bracket for each plunger rod, and each bracket having a slot 22 receiving the equalizing spring 20. The 75 bracket projects above the equalizing spring and is provided with an opening 23 disposed in a line with the openings in the vertical flanges of the angle bars 19, whereby the plunger rods 18 are mounted to slide 80 through the opening 23 of its respective bracket. In this manner the plunger rods are independently adjustable transversely of the table top 13 so as to give to the spring leaf 17 a uniform or regular configuration 85 90 consistent with the particular pattern after which the leaf is to be designed. Pivots mounted on each bracket 21 is a cam shaped lever 24 which when brought into engagement with the plunger rod 18 holds the latter fixed in its adjusted position.

A shaft 25 is disposed beneath the table top, and mounted for partial rotation, and fixed upon said shaft and projecting forwardly therefrom is a pair of spaced levers 105 26, having their forward extremities connected through the instrumentality of a bar 27. Disposed in juxtaposition to each of the levers 26 is a lever 28 fixed upon the shaft 25 and rising therefrom, the upper ex- 110

tremity of each lever 28 having pivotal connection with an arm 29 which projects rearwardly from the lever 28 and operatively connected with a clip 30 secured to the 5 equalizing spring 20. In other words the arms 29 provide a connection between the levers 28 and the equalizing spring so that when the shaft 25 is rotated in one direction the equalizing spring is brought forwardly 10 forcing the plunger rods 18 against the heated spring leaf 17, or other piece of material to be worked, causing the latter to assume a configuration similar to the pattern 16. It is of course manifest that 15 the shaft 25 is rotated in the proper direction to operate the plunger rod 18 by depressing the bar 27, either by hand or by foot, and when the bar 27 is relieved of this pressure, the springs 30 having their 20 corresponding extremities secured to fixed supports 31 and their opposite extremities secured to a lever 32 fixed upon the opposite extremity of the shaft 25, operates to automatically return the component parts of 25 the machine to their normal or inactive position.

The table top 13 can be quickly and easily raised or lowered through the instrumentality of the screws 34 to accommodate different widths of springs or other material 30 to be worked upon, the screws 34 being connected with the top 13 and threaded through suitable brackets 31 disposed adjacent each of the four corners of the top as shown.

While it is believed that from the foregoing description the nature and advantages of the invention will be readily apparent I desire to have it understood that what is herein shown and described is merely illustrative of the preferred embodiment of 40 the invention to which I do not limit myself and that such changes in the construction and arrangement of parts may be resorted to when desired as fall within the scope of what is claimed.

45 What is claimed is:—

1. A metal forming machine comprising a support, a pattern mounted thereon, spaced parallel apertured guides, plunger rods arranged to slide through said guides, an

equalizer spring disposed edgewise beneath and in parallelism with said guides, a member for each rod having a bifurcated extremity straddling said spring, said member having an opening in which said rod slides, said rods being susceptible of independent 55 adjustment relatively, a cam associated with said member and engaging said rod for holding the latter fixed in its adjusted position, and means for moving said rods in unison toward and away from said pattern. 60

2. A metal forming machine comprising a support, a pattern mounted thereon, spaced parallel guides, a plurality of plunger rods mounted to slide through said guides, an equalizer spring disposed beneath and in 65 parallelism with said guides, a member for each rod, secured to said spring and having an opening through which said rod passes, said rods being susceptible of independent relative adjustment, means carried by said 70 member for engagement with said rod for holding the latter in its adjusted position, and means for moving said rods in unison toward and away from said pattern.

3. A metal forming machine comprising 75 a support, a pattern mounted thereon, a plurality of spaced plunger rods mounted for movement toward and away from said pattern, guides for said rods, an equalizer spring disposed in parallelism with 80 said guides, a connection between said spring and each of said rods for holding the latter fixed relatively to said spring, a shaft journaled on the support beneath said rods, levers projecting upwardly 85 from said shaft adjacent the opposite ends thereof, members secured to the spring at spaced intervals, an arm pivotally associated with the upper extremity of each lever and having connection with the adjacent 90 member on said spring, whereby the rods are actuated toward the pattern when the shaft is rotated in one direction, means for rotating the shaft in said direction, and means for automatically reversing the rotation of said shafts and returning said 95 rods to normal position.

In testimony whereof I affix my signature.
SAMUEL B. FINEGAN.
